F. M. GODDARD

ANTIINDUCTION DEVICE

Filed Sept. 22, 1921

Inventor:
Frederick M. Goddard,

by W. E. Beatty, atty.

UNITED STATES PATENT OFFICE.

FREDERICK M. GODDARD, OF BROOKLYN, NEW YORK, ASSIGNOR TO WESTERN ELECTRIC COMPANY, INCORPORATED, OF NEW YORK, N. Y., A CORPORATION OF NEW YORK.

ANTIINDUCTION DEVICE.

Application filed September 22, 1921. Serial No. 502,427.

To all whom it may concern:

Be it known that I, FREDERICK M. GODDARD, a citizen of the United States, residing at Brooklyn, in the county of Kings, State 5 of New York, have invented certain new and useful Improvements in Antiinduction Devices, of which the following is a full, clear, concise, and exact description.

This invention relates to anti-induction 10 devices, its object being to provide a compact and convenient arrangement of means for preventing magnetic disturbances in adjacently placed electro-magnetic devices, which means is readily removable to allow 15 for easy access, inspection, adjustment and repair of such apparatus.

When two pieces of apparatus, such as relays, are placed near one another, the magnetism of the one affects the other. If the 20 magnetism of the one is changing, a current is induced in the other and a condition exists which is termed "cross-talk." If the magnetism of the one is not changing but remains stationary, the characteristics of the 25 other are affected so that it may be energized by a smaller number of ampere turns, or it may require a larger number of ampere turns, or its releasing conditions may be changed so that it may not operate in the 30 manner for which it is designed and adjusted, in which case, a condition exists which is termed "cross-fire." Through extensive experiments, it has been discovered that shells of conducting material placed 35 about relays will prevent cross-talk, but will not prevent cross-fire unless such shells are also made of magnetic material. When rows of relays which are not in talking circuits are placed adjacent one another and 40 cross-talk is not objectionable, it has been found that a simple sheet of magnetic material placed between the rows is an effective shield against cross-fire. Hence, an apparatus rack comprising means for removably 45 mounting the shields between rows of apparatus has been devised as a convenient and effective means for mounting great numbers of relays and other electromagnetic devices and overcoming the difficulties contingent on 50 such close association which have heretofore been encountered.

In the drawings, Fig. 1 is a side sectional view, Fig. 2 is a front view, and Fig. 3 is a top view showing the organization of stand-

ards, apparatus mounting plates, shield 55 holders and shields. Fig. 4 is a sectional perspective view showing the method of securing the shield holders when the apparatus mounting plates are secured to the back of the standards; and Fig. 5 is a sectional 60 perspective view showing the method of securing the shield holders when the apparatus mounting plates are secured to the front of the standards.

The standards 1 may be in the form of 65 I beams as shown in the drawings, or any other convenient form of structural steel. Secured to the I beams are apparatus mounting plates 2 on which are mounted rows of relays 3 and 4. The flat type relay 70 such as 3 may be secured to the mounting plates by screws and the round type relay such as 4 may be bolted to the mounting plates. Channel bars 5 bent in the form of an L are riveted to securing plates 6, which 75 are secured to the mounting plates by the same screws that attach the mounting plates to the I beams. These channel bars may be secured either to the back of the mounting plates as shown in Fig. 4, or to the front of the mounting plates as shown in Fig. 5, so that they will protrude between the rows of relays in the same direction as the axes of the relays and form a convenient 80 means for holding the magnetic shields. 85 These shields 7 comprise a plate of magnetic material long enough to fit in the recesses of the channel bars. Secured to the back and front edges of this shield 7 are wooden or fiber strips 8 which may be used as designation strips and on which characters representing the position of a relay in its circuit may be printed. In order to hold the plate 7 securely in place, springs 9 are riveted 90 near the ends of the plate and serve to hold the shield firmly within the recesses of the channels. Extensions 10 of the securing plate 6 are provided to prevent the shield 95 100 105 7 from being pushed too far backward. When the channel bars 5 are secured to the front of the mounting plates 2, as shown in Fig. 5, the extensions 10 also serve to space adjacent mounting plates so that the designation strip 8 may pass between them.

This organization, as described, provides for the ready removal of the shield 7 for inspection, adjustment and repair of the relays.

What is claimed is:

1. An apparatus rack comprising standards, apparatus mounting plates secured to said standards, rows of apparatus mounted on said plates, channels mounted on said standards between said plates, and shields arranged to slide in said channels so as to be interposed between adjacent rows of said apparatus.
2. An apparatus rack comprising standards, apparatus mounting plates secured to said standards, rows of apparatus on said plates, channels mounted on said standards between said plates, and shields of magnetic material arranged to slide in said channels so as to be interposed between adjacent rows of said apparatus.
3. An apparatus rack comprising standards, apparatus mounting plates secured to said standards, rows of apparatus mounted on said plates, removably mounted shields between said rows, and designation strips attached to said shields.
4. An apparatus rack comprising standards, apparatus mounting plates secured to said standards, rows of apparatus mounted on said plates, channels mounted on said standards between said plates, shields arranged to slide in said channel so as to be interposed between adjacent rows of said apparatus, and designation strips attached to the edges of said shields.
5. An apparatus rack comprising standards, apparatus mounting plates secured to said standards, rows of apparatus mounted on said plates, channels mounted on said standards between said plates, shields arranged to slide in said channels so as to be interposed between adjacent rows of said apparatus, and springs for retaining said shields in said channels.

In witness whereof, I hereunto subscribe my name this 20th day of September A. D., 1921.

FREDERICK M. GODDARD.
